(57) **CLAIM**

The ornamental design for spinal column corrective device, as shown and described.

DESCRIPTION

FIG. 1 is a perspective view of one side and the top of the spinal column corrective device according to one embodiment of my new design;

FIG. 2 is a top view thereof;

FIG. 3 is a left side view thereof;

FIG. 4 is a right side view thereof;

FIG. 5 is a bottom view thereof;

FIG. 6 is a front view thereof; and

FIG. 7 is a back view thereof.

FIG. 8 is a perspective view of one side and the top of another embodiment of my new design;

FIG. 9 is a top view thereof;

FIG. 10 is a left side view thereof;

FIG. 11 is a right side view thereof;

FIG. 12 is a bottom view thereof;

FIG. 13 is a front view thereof; and,

FIG. 14 is a back view thereof.
